3 Claims. (Cl. 103—131)

Work producing and work consuming machines and engines are known, in which a disk, a ring or the like is provided with projections which extend substantially radially outwardly or inwardly and which, driven by an eccentric or by a crank, perform movements oscillating in a circle, so-called paracyclic movements. The disk or the ring at the same time does not participate in the rotary movement of the eccentric around its axle but every point of the moved part oscillates along a circle the radius and direction of rotation of which are similar to those of the eccentric.

In the known machines of this type the control of the medium delivered by the machine (liquid, steam or gas) or of the medium producing the energy and fed to the machine was placed in such parts of the machine which carry out a purely rotary movement, that is no paracyclic movement. In the case of high running speeds the control parts therefor travel at high relative speeds and are consequently subject to heavy wear.

According to the invention the advantage offered by the paracyclic movement is utilized, namely the advantage of low speed, also for the control in spite of the high speed of rotation. For this purpose a rolling disk exerts the control by outwardly or inwardly directed projections or by slots in that by these elements it uncovers or covers control channels, which are provided in the side walls between which the rolling disk slides.

According to the invention it is possible to perform the separate duties of displacement and control by means of a single rolling disk with paracyclic movement. The projections of the rolling disk and the recesses of the casing therefor may be so shaped that the third duty, namely the guiding of the rolling disk, is also fulfilled.

Whereas in simple instances all three functions, namely displacement, control and guiding can, as above mentioned, be entrusted to a single rolling disk, it is possible according to the invention to distribute these functions to different disks as the conditions may require.

As a rule the rolling disks are merely separated as regards displacement and control. The guiding may be effected as desired by the piston disk or by the control disk or by separate elements, which here need not be considered.

In the case above mentioned, in which only two rolling disks are employed, both disks are mounted on the same eccentric bushing. Both disks slide well packed between the casing walls.

Whereas the control disk regulates the admission and discharge of the medium to be delivered to and from the piston disk, the piston disk has only to effect the displacement and packing.

Both, the piston disk and also the control disk, may according to the invention be further subdivided, that is on one eccentric bushing one or more piston disks and one or more control disks may be mounted.

The eccentricities of the individual disks may be mutually displaced through 180° or 120° or any other necessary angle. Thus, for certain instances, a desirable equalization of power can be brought about. The eccentricities of the individual disks may be otherwise relatively displaced.

It has also been found, that in one machine or in machine units connected in series axial thrusts occur, which present difficulties owing to the disk-shape of the pistons. These difficulties are overcome according to the invention in that both the admission and also the discharge channels are situated on both sides of the rolling piston, so that the admission takes place on both sides of the pistons. By this symmetrical pressure loading of the piston the production of axial thrusts is prevented from the outset.

The invention provides further for the arrangement of several groups of piston disks (with displacement effect), one group of which being allowed to run as motor, for example by admission of steam and the other group as working machine, for example as compressor or pump. Moreover, the toothed rim of a rolling disk can be subdivided into parts working as motor and as pump.

The subdivision of the rolling disks need not be effected only by arranging side by side in axial direction, but it can also be effected in radial direction, that is by arranging concentric roller disk groups, without departing from the scope of the invention.

Several embodiments are illustrated by way of example in the accompanying drawings in which:—

Fig. 1 shows in longitudinal section a pump of simple construction for small efficiencies, in which the control and piston disks are united to form one rolling disk.

Fig. 2 shows an outer elevation of the pump with its electric driving motor and the cable lead. The electric motor and the type of drive are well known.

Fig. 3 is a cross section on line 3—3 of Fig. 1. The pressure slots are situated above the plane

of the picture and are therefore shown in broken lines.

Fig. 4 shows a two-stage pump in longitudinal section, the individual stages and the drive being identical to those illustrated in Figs. 1 and 2.

Fig. 5 shows in longitudinal section a machine of horizontal type, in which two combined rolling disks are employed, but these disks are not connected in series as in Fig. 4 but in parallel.

Fig. 6 is a cross section on line 6—6 of Fig. 5.

Fig. 7 is a longitudinal section of a two-stage compressor.

Fig. 8 is a cross section on line 8—8 of Fig. 7.

Fig. 9 shows in longitudinal section a machine for converting pressure.

Fig. 10 is a section on line 10—10 of Fig. 9 showing in end view the rolling disk with parabolic motion.

As shown in Fig. 3 the eccentric rotates in the direction of the arrow 1. During the small oscillation which corresponds to the angle γ , the disk 2 performs a stroke in the direction of the arrow 1. By means of the two packing points 3 and 4 the space at the instant of the movement in question between the circumference of the disk 2 and the inner wall of the stationary disk 5 is divided into two parts. The liquid contained in the lower space, that is below 3—4 in the drawing, is therefore partly displaced whilst fresh liquid is drawn into the space at the top in the drawing. In the example described the stationary wall 5 is of approximately the same thickness as the driven disk 2. Above and below the two disks 2 and 5 (Fig. 1) two further disks 6 and 7 are located which have suction and pressure slots and which are clamped in the manner shown in Fig. 1 together with the stationary disk 5 between thick flanges 8 and 9 of the machine casing. The movable disk 2 has a number of teeth 10, the shape of which depends merely upon the necessity of packing which will be hereinafter described. The teeth may be made in many other shapes. They need not lie in the moved disk 2. They might just as well be provided on the stationary disk 5 or on a part of the casing. Other solutions can also be imagined. The feature of the invention consists in that the surroundings of the projections 10 ensure a good packing in certain positions in conjunction with the correspondingly constructed walls 11 of the counter disk 5.

During the short movement in which the angle γ is traversed, the edges 3 and 4 of the stationary and working disk must contact as tightly as possible so that the liquid enclosed between the working disk and the wall cannot flow back but can be pressed in opposition to the conveying pressure through the pressure slots 17, shown in dot-dash lines in Fig. 3, in the upper disk 7.

At the instant in question the tooth edges 12 also slide on the counter edge 13 of the stationary disk in such a manner that a good guiding of the working disk 2 is obtained.

The flanks 14 and 15 of the teeth serve for controlling the admission and discharge ports. Fig. 3 shows that during the time in which the small angle γ is traversed the admission channels 16 in the lower half of the drawing are closed, whereas the pressure slots 17 remain more or less open. In the upper half of the drawing the admission channels 16 are open and the pressure slots 17 closed. In other words: the pressure

period is represented in the lower half of Fig. 3 and the suction period in the upper half.

The packing procedure at 3 and 4 and the guiding at 12 and 13 travels from tooth to tooth like the suction and pressure procedures. The shapes of the teeth and of the apertures may be so chosen that neighbouring teeth participate in the packing or guiding.

The construction of the machine is illustrated in Figs. 1 and 2. 18 is the extended shaft of the motor shown in Fig. 2, which is journaled in the two bearings 19 and 20. The axial thrust is taken up in known manner, for example by a longitudinal bearing in the motor. On the shaft 18 an eccentric 21 is keyed which acts on the working disk 2 through the intermediary of a pressure sleeve 22. The liquid enters the lower part 24 of the casing from 23 and thence through the admission slots 16 in the disk 6.

The flange 25 serves for supporting the motor (Fig. 2), which in the example chosen is assumed to be liquid-proof enclosed.

The liquid conveyed passes through the pressure slots 17 of disk 7 into the upper part 26 of the casing having a connection 27 to the pressure conduit.

The disk 28 keyed on the shaft is utilized for the dynamic counter balancing of the moved machine parts, especially the eccentric.

In Fig. 4 a two-stage pump is illustrated, the two working disks 2 and 2' of which are driven by the same eccentric. The eccentric for driving the second working disk 2' may be arranged displaced relative to the first eccentric.

The axial pressure exerted upon the disks and which is produced by the difference between the admission and conveying pressures may be equalized by connecting in parallel two working disks (with lower and upper admission) or by similar measures. In the case of multistage machines according to the invention different groups of stages may be formed for this purpose which have oppositely directed axial forces. These groups may be connected in parallel or in series. It is also possible to make provision in a simple manner for connecting two simple working disks as desired in parallel or in series so that twice the quantity of water can be delivered by the same motor to a certain height or to twice the height with the same quantity of water.

Fig. 5 shows a pump, in which two rolling disks are connected in parallel. Both rolling disks are composite disks, which exert simultaneously a displacing and controlling effect. In the casing 30, 31 composed of several parts, the shaft 32 is journaled in two ball bearings 33 and 34. A groove 35 serves for accommodating the clutch to the driving motor which is not shown in the drawing for the sake of clearness. Two eccentrics 36 and 37 made in one part with the shaft 32 are provided, mutually displaced through 180°. These eccentrics act through the intermediary of two balls or roller bearings 38 and 39 on rolling disks 40 and 41 which therefore perform similar movements oscillating in a circle displaced through 180°. Four concentric rings 42, which are pressed by rubber springs 43 or in some other manner against the rolling disks 40 and 41, exert like the known stuffing boxes the packing between the pump compartment proper and the compartment 44 which communicates with the atmosphere through a known discharge. Cups 45 and 46 fixed the one on the other in known manner protect the ball or roller bearings against water splashed from the pump compartment.

Fig. 6 is a cross section on line 6—6 of Fig. 5.

Fig. 7 is a longitudinal section of a two-stage compressor.

Fig. 8 is a cross section on line 8—8 of Fig. 7.

Fig. 9 shows in longitudinal section a machine for converting pressure.

Fig. 10 is a section on line 10—10 of Fig. 9 showing in end view the rolling disk with parabolic motion.

Two eccentric masses 47 and 48 are keyed on the shaft 32 and counterbalance in known manner the eccentrically acting forces of the two rolling disks 40 and 41.

5 The two rolling disks slide tightly between the four casing walls which are formed by suitable division of the casing. A plate 49 with counter teeth 50 is pushed into the main portion 30 of the casing. This plate determines the width for 10 the rolling disk 40. An intermediate element 51 traversed by several channels bears against the plate 49 and limits the right side of the rolling disk 40 and the left side of the rolling disk 41. Then follows as last part to be inserted into the 15 main part 30 of the casing a second counter disk 52. This disk is limited by the cover 31 of the casing, which serves for closing the whole pump casing and is connected in known manner to the remaining parts.

20 The liquid passes into the casing in the direction of the arrow 53. It then immediately divides into three arms. The discharge liquid flows out from the casing in the direction of the arrow 54 and is also divided in three arms. The 25 purpose of this subdivision is the double-sided utilization of both rolling disks with the pressure both of the admission and also of the discharge liquid. Owing to the fact that both pressures act simultaneously on both sides of the two rolling 30 pistons, the production of a unilateral axial force is prevented (as is possible with the simple examples, i. e. that shown in Fig. 1).

In practice this effect is attained in that both the suction slots 55 and also the pressure slots 56 lie directly opposite one another in the two casing walls, between which each of the rolling disks 40 and 41 slides tightly.

The parts illustrated in Fig. 6 are similar to those described with reference to Figs. 1 and 3, only the shapes of the teeth are somewhat different. The shape of the teeth and the mutual displacement of the two rolling disks not only relative to the eccentricities but also as regards the tooth pitch enables the greatest possible 45 equalization of forces and uniformity of delivery.

As shown in Fig. 6 the rolling disks 40 and 41 not only perform the control and displacement in the manner already described but also the guiding, which ensures the unimpeded running 50 along of the eccentric circle for all points of the rolling disk.

In Figs. 7 and 8 a two-stage compressor is illustrated. Both stages are accommodated in one single rolling disk. The journalling of the shaft, 55 the construction and journalling of the rolling disk correspond to those of Fig. 5. The compressor operates in the following manner: The air at atmospheric pressure passes in the direction of the arrow 78 into the annular space 79 and thence, 60 when the piston is in suitable position, through the suction slots 80 into the corresponding working spaces. The suction slots 80 are controlled by the edge 81 on the piston 82. The shape of the teeth 83 is so chosen that the least possible 65 play exists between the piston and the casing wall. The packing and guiding are effected by the round pins 84 which are mounted on corresponding extensions 85 of the teeth 83. After the compression has been completed the control edge 86 70 of the piston exposes the pressure slot 87. The compressed air passes in the direction of the arrow 88 to the intermediate cooler and thence in the direction of the arrow 89 to the high pressure part of the compressor. As can be seen from the 75 drawings the channels belonging to the control

edges 81, 86, 95 and 96 are merely milled out portions in the rolling disk. The size of the diameter of a high pressure piston is determined partly by the prescribed compression ratio. The high pressure piston 90 is rigidly connected to the casing 92 by means of screws 91. The inner portion of the low pressure piston 82 therefore has become, so to speak, the paracyclically moved cylinder of the stationary high pressure piston 90.

The control slots for the high pressure part are 80 93 and 94. The corresponding control edges in the moved part 82 are designated by 95 and 96. The highly compressed air leaves the compressor casing in the direction of the arrow 97.

Contrary to the illustrations in Figs. 7 and 8 85 the inflow grooves of the high pressure part may be on the opposite side of the rolling disk to the inflow grooves of the low pressure part. This arrangement enables a good equalization of the axial forces, which are produced during the compression in the low pressure and high pressure part.

Fig. 9 illustrates a machine which serves for considerably increasing or decreasing pressures. Both parts, necessary for changing the pressure, 100 namely the motor and the pump, are accommodated in one single toothed rim. It is apparent, that in this arrangement the mounting can be very simple or be omitted.

Suppose that at a certain instant the rolling 105 disk 99 be in the position shown in Fig. 15 relative to the counter disk 100. In this position the two packing points 101 and 102 determine the separation of the zone of the working pressure from the remaining zones. On the left 110 of the connecting line 101—102 the working pressure exists, that is the pressure of the working liquid, owing to the fact that the working liquid entering in the direction of the arrow 98 having distributed itself in the annular space 103, penetrates 115 into the working chamber 105 through the slots 104. A rotary force therefore acts on the piston in the direction of the arrow 106.

At the instant under consideration the maximum movement on displacement undoubtedly 120 exists in the space 107, which therefore may be regarded as high pressure space for the movement phase illustrated. As shown in Fig. 10, the channel 108 in the right hand casing wall according to Fig. 9 is brought into communication 125 with the high pressure space 107 by the control slot 109, so that therefore the useful high pressure liquid may be continually delivered into the annular space 110 and thence through the connection 111 to the point of consumption. At 130 the same time the working liquid, which has given up its energy to the rolling piston, escapes from the spaces 112 and 113.

As shown in Fig. 8 a connection is established 135 for this purpose between the spaces 112 and 113 on the one hand and the annular space 115 on the other hand by the control slot 114. The used up working liquid can therefore escape into the open through the connection 116. A journalling proper of the rolling piston 99 is not necessary 140 in the present example, as the energy transmission takes place within the rigid rolling piston.

Therefore it is sufficient in this instance, to assist the usual guiding by the tooth heads by means of two rollers 117 which are mounted on 145 a common pin 118 and support the rolling piston on the pins 119 or on the ring path 120.

The dividing up of the entire tooth spaces of the rolling disk as described is only to be regarded as an example. The designer can inter- 150

change the three groups of spaces (admission, discharge of the high pressure liquid, discharge of the working liquid) to suit requirements.

I claim:—

- 5 1. A machine of the character described comprising a casing having side walls, an oscillating rolling piston slideable within the casing in intimate contact with the side walls, said casing having circumferentially spaced recesses therein, substantially radial projections on the piston respectively extending into the recesses, said casting walls having pairs of admission and discharge ports respectively registering with each recess and said projections movable over the ports to control flow therethrough.
- 10 2. A machine of the character described comprising a casing having internal circumferential

recesses and side walls with pairs of admission and discharge ports therein respectively associated with a recess, an oscillating rolling piston guided tightly between said side walls and a series of radial projections on the piston respectively extending into the recesses to control flow of fluid through the ports.

15 3. A machine of the character described comprising a stationary casing having side walls with pairs of admission and discharge ports therein, an oscillating piston within the casing moving in contact with the walls thereof and a plurality of circumferential radially extending elements on the piston, each associated with a pair of ports for controlling the flow of fluid through the ports.
